Filed May 2, 1960, Ser. No. 60,410

Term of patent 14 years

(Cl. D71—1)

Fig. 4.

Fig. 5.

FIGURE 1 is a perspective view of a transport helicopter embodying my new design;

FIGURE 2 is a top plan view thereof;

FIGURE 3 is a side elevation of the transport helicopter, the opposite side being the same in appearance;

FIGURE 4 is a front elevation thereof in flight position; and

FIGURE 5 is a front elevation thereof with the wing tips lowered in position for landing.

Portions of the rotor blades are broken away in FIGURES 2, 4 and 5 for convenience of illustration only.

I claim:

The ornamental design for a transport helicopter, as shown and described.
